(57) **CLAIM**

The ornamental design for a dish drying rack, as shown and described.

DESCRIPTION

FIG. 1 is an isometric view of a dish drying rack according to an embodiment;

FIG. 2 is a top view of the dish drying rack illustrated in FIG. 1;

FIG. 3 is a bottom view of the dish drying rack illustrated in FIG. 1;

FIG. 4 is a side view of the dish drying rack illustrated in FIG. 1;

FIG. 5 is a side view, which is opposite the side view of FIG. 4, of the dish drying rack illustrated in FIG. 1;

FIG. 6 is a front side view of the dish drying rack illustrated in FIG. 1; and,

FIG. 7 is a rear side view of the dish drying rack illustrated in FIG. 1.

The broken lines in the drawings form no part of the design to be patented.

1 Claim, 7 Drawing Sheets
